(57) **CLAIM**

The ornamental design for an exhaust trim tab for a boat, as shown and described.

DESCRIPTION

FIG. 1 is a top perspective view of an exhaust trim tab for a boat, showing the new design.

FIG. 2 is a front view thereof;

FIG. 3 is a rear view thereof;

FIG. 4 is a side view thereof;

FIG. 5 is a top view thereof;

FIG. 6 is a bottom view thereof; and,

FIG. 7 is a cross-section view of an exhaust trim tab for a boat taken along line 7-7 in FIG. 2.

The broken lines illustrate portions of the exhaust trim tab that form no part of the claimed design.
